Application May 7, 1952, Serial No. 286,646

9 Claims. (Cl. 340—348)

This invention relates to a coding device and, more particularly, to such a device for selectively producing any one of a plurality of predetermined coded impulse sequences under the control of an operator.

Prior devices of a similar nature are large in physical size so that it is impossible or extremely inconvenient to locate such a device in a small space adjacent an operator's position in an aircraft or other vehicle. Also, these large coding devices, because of the remote location thereof from the operator, are subject to many inherent disadvantages among which is the necessity of utilizing long wire runs and a large number of relays in order to provide for remote control of the coding device. Such electrical equipment is often the source of considerable radio interference and accordingly necessitates the use of elaborate noise suppression or filtering equipment. In addition, the remote control of available devices of this character presents the possibility of errors inasmuch as it is impossible for the operator to determine that the proper sequences of impulses are being transmitted or produced by the device. These prior devices are also subject to the inherent disadvantage that it is necessary to change the complete sequence of code impulses each time a new sequence is desired, regardless of the fact that certain permutations of impulses may be common to all of the desired sequences. Further, in available prior devices, it is difficult if not impossible fixedly to secure code bars or other similar members having indicia of the desired intelligence to be transmitted in an immovable position.

Accordingly, one object of this invention is to provide an improved coding device of unitary construction which is small in physical size so that it may easily be mounted in an instrument panel closely adjacent an operator's position.

Another object of the invention is to provide a coding device in which any one of a plurality of predetermined code impulse sequences may be easily and quickly selected by an operator.

It is a further object of the invention to provide a coding device in which code bars or other similar members carrying indicia are positively secured against motion during the period of impulse transmission.

Another object of the invention is the provision of a coding device in which the sequence of code impulses to be transmitted is capable of being changed in its entirety or only in part.

A still further object is the provision of a coding device having a minimum of electrical parts so as to reduce both the amount of equipment required and the amount of radio interference produced by the device.

One embodiment of the invention constructed in accordance with the foregoing objects includes a plurality of radially extending code bars or fingers provided with undulations representative of a plurality of different code impulse sequences which it is desired to transmit. The code bars are secured to an actuating shaft which is rotatable to select and move any of the plurality of fingers or bars into operative engagement with a spring loaded

2

contact actuating plunger assembly which is secured to a disc carrying a plurality of contact means. The disc is rotated by a motor or other similar means so that the contact actuating plunger is progressively moved along the undulations of the selected code bar, thereby sequentially to actuate the contact means to produce a series of impulses in accordance with the undulations over which the actuating plunger is moved. The shaft to which the disc is secured is also provided with a plurality of axially spaced cam members angularly displaced from each other to actuate a plurality of fixed position contacts in a desired sequence representative of a group of pulses which may be common to the group of impulses produced by each of the movable fingers. The shaft to which the fingers are secured is also provided with spring actuated locking means for securing the fingers in a predetermined selected position, and which is capable of being disengaged or unlocked by the operator when it is desired to move a different code bar into engagement with the contact actuating means.

Other objects and advantages of this invention will become apparent from a consideration of the following specification in conjunction with the drawings wherein:

Fig. 1 is a front elevational view of a coding device embodying the invention;

Fig. 2 is a fragmentary cross sectional view taken along line 2—2 in Fig. 1;

Fig. 3 is a cross sectional view taken along line 3—3 in Fig. 1;

Fig. 4 is a fragmentary enlarged cross sectional view taken along line 4—4 in Fig. 1; and

Fig. 5 is a schematic circuit diagram showing apparatus for utilizing the coding device shown in Figs. 1 to 4, inclusive.

Referring now to the drawings wherein like reference numerals indicate the same elements throughout the several views, and more particularly to Figs. 1, 3, and 5 of the drawings, a coding device indicated generally as 10 is provided with a code selecting device, indicated generally as 12, and an impulse producing means indicated generally as 14. The code selecting means 12 includes a plurality of arcuate radially extending code bars or fingers 16 having a plurality of cam portions or undulations 18 formed in the uppermost edge thereof. These fingers 16 are rigidly secured to an operating shaft 20 rotatably mounted in a frame member 22 which may be a wall surface instrumental panel. By rotating the shaft 20, any one of the plurality of code fingers 16 may be moved into operative engagement with one of a pair of contact actuating assemblies 24 in the impulse transmitting means 14. The assemblies 24 and a plurality of contact means 26 are secured to a disc 28 which is rotated so that the actuating assemblies 24 are moved up and down in accordance with the progressively encountered cam surfaces 18 formed in the code bar 16 with which they are in engagement. These reciprocating movements of the assemblies 24 sequentially actuate the contact means 26 to produce a series of impulses which are utilized in external impulse responsive apparatus.

In order to secure the code bars 16 to the operating shaft 20 therefor, the upper ends of the bars 16 are interposed between a pair of vertically spaced plates 30 and 32, the lower plate 32 being formed with a plurality of peripherally spaced slots 34 within which the upper ends are received. The two plates 30 and 32 are moved toward each other by a pair of nuts 36 and 38 which threadedly engage the shaft 20 so as rigidly to clamp the plurality of fingers or bars 16 in position therebetween. A plurality of washers 40 are interposed between the nuts 36, 38 and the plates 30, 32. The fingers 16 are maintained in their radially spaced relationship because of the provision of the plurality of peripherally spaced slots 34 pro-

vided in the upstanding edge of the plate 32. A lower spacer member 42 having an upstanding lip in which a plurality of peripherally spaced slots 44 are formed is secured to an intermediate portion of the lower edge of the bars 16 to aid in maintaining the desired spacing between the code fingers 16. Anyone of the bars or fingers 16 may be easily replaced by merely rotating one of the nuts 36 or 38 out of clamping engagement with the plates 30 and 32 and removing the finger 16 to be replaced.

In order to secure a particular selected one of the plurality of bars 16 in a selected transmitting position, locking means indicated generally by 46 is provided. This locking means includes an annular sleeve 48 secured to the shaft 20 by a machine screw 50, and provided at its upper extremity with a plurality of radially extending teeth 52 equal in number to the number of fingers 16. In a locking position, the teeth 52 (Fig. 1) are received within a plurality of slots 54 formed in a depending lip of a plate 56 which is secured to a bracket 58 supported on the frame 22. The teeth 52 are maintained in locking engagement within the slots 54 by means of a compression spring 60 which is interposed between an upper surface of the bracket 58 and the lower surface of a collar 62 which is secured to the shaft 20 by means of a pin 64 extending through said shaft. The coil spring 60 urges the shaft 20 in an upward direction and, accordingly, maintains the teeth 52 in locking engagement within the plurality of slots 54.

To provide for moving a different cam finger or arm 16 into engagement with the contact actuating assembly 24, an operator manually moves the shaft 20 in a downward direction as shown in Figs. 1 and 3 by a manual manipulation of a knob 66 secured to one end of the shaft 20. This downward movement of the shaft 20 compresses the spring 60 and moves the plurality of fingers 16 into the position shown in dash lines in Fig. 3. In this position, the fingers 16 are moved out of engagement with the assembly 24 and the teeth 52 are moved out of locking engagement with the slots 54. Thereupon, the operator manually rotates the knob 66 to move a different one of the code bars 16 into position beneath the assembly 24 and removes the downward pressure exerted upon the knob 66. The shaft 20 is moved vertically upward as shown in Figs. 1 and 3 under the action of the coil spring 60 to place the selected finger 16 in engagement with the plunger 24 and also to move the teeth 52 into locking engagement with the plurality of slots 54. The knob 66 is provided with an integral pointer 68 which cooperates with a dial plate 70 secured to the frame 22 to facilitate proper selection of the desired code bar 16. Obviously the inter-engagement of the teeth 52 with the slots 54 positively prevents any displacement of the fingers 16 from the selected position.

The impulse producing means 14 which is actuated in accordance with the intelligence of information coded on the plurality of cam fingers or bars 16 includes the disc 28 upon which are secured the pair of actuating plunger assemblies 24 in a position diametrically opposite each other. These plunger assemblies are reciprocated in a vertical direction to actuate the contact means 26 by means of a roller 72 (Fig. 1) which is held in engagement with the upper undulating surface of the finger 16 disposed immediately therebelow. The roller 72 is rotatably mounted between a pair of bifurcated arms 74 formed in a shaft 76. The shaft 76 is freely mounted in a pair of brackets 78 secured to the disc 28 and is normally urged outwardly by a compression spring 80 which is interposed between the innermost bracket 78 and a collar 82 keyed to the shaft 76 adjacent the lower bracket 78. Since the coil spring 80 resiliently urges the shaft 76 outwardly from the center of the disc 28, the roller 72 is held in engagement with the upper surface of the finger 16 positioned therebelow. This downward movement of

the shaft and roller is limited by the engagement of a collar securing pin 84 with the outermost bracket 78.

The pair of contact means 26 which are utilized to produce the impulses of current include a pair of electrically insulated contact arms 86 which are secured to the disc 28 so as to extend parallel to each other. A pair of contact points 88 are provided at one end of these arms to permit electrical interconnection therebetween and the other ends are insulated from each other. The innermost arms 86 are resiliently interconnected by a tension spring 90 so that these innermost arms are constantly urged into contact with a conducting slip ring 92 which is supplied with electrical energy through a conductor 94 and a brush 96 (Fig. 1). The outermost arms 86 are both electrically connected to ground so that upon actuation of the shaft 76 to move upwardly, as shown in Fig. 3, a circuit from a grounded battery 98 (Fig. 5) through a code utilization circuit 100 is completed through conductor 94, brush 96, slip ring 92, innermost arms 86, contacts 88, and thence to ground through the outermost arms 86. As the roller 72 is moved over the undulations or cam surfaces 18 formed in the fingers 16, the shaft 76 is intermittently urged upwardly to move the contact 88 positioned on the outermost arm 86 into engagement with the contact 88 positioned on the innermost arm 86, thereby to produce a series of impulses which may be utilized in any desired manner in the circuit means 100. Obviously, only one of the actuating assemblies 24 will be utilized at any one particular time, and it is within the scope of this invention to provide any number of assemblies 24 and contact means 26 spaced peripherally about the disc 28.

In order to rotate the disc 28 and produce corresponding relative movement between the selected coded cam finger 16 and assembly 24, the disc 28 is rigidly secured to a shaft 102 which is rotatably mounted on the frame 22. The shaft 102 is preferably positioned coincident with the axis of the generation of engaged arcuate finger 16 so that the curved edges of this finger and the disc 70 are concentric with each other. The shaft 102 is rotated in a predetermined direction at a desired speed by means of a motor 104 (Fig. 5) which is secured to a shaft 106 (Fig. 1) through a pair of gears 108 and 110. Obviously, the slip ring 92 which is also secured to the shaft 102, is electrically insulated therefrom by any desired means such as a dielectric sleeve 112 which is interposed between the outer surface of the shaft 102 and the inner surface of the slip ring 92. The motor 104 may comprise any one of the numerous motors well known in the art, and may be either a constant speed type or a type which is capable of being adjusted to operate at a plurality of different speeds under the control of an operator.

In order to provide a plurality or a sequence of current impulses which is common to all of the plurality of code impulse sequences provided by the plurality of cam fingers 16, a plurality of contact means 114 (Figs. 1 and 4) are secured to the frame 22 at spaced positions thereon. A lowermost switch blade 116 of each of the contact means 114 is disposed in alignment with one of a plurality of cams 118 which are secured to the shaft 102. The cams 118 are displaced angularly about the axis of the shaft 102 from each other so that each cam closes a circuit from ground through the contact means 114 associated therewith, conductors 120 (Fig. 5), circuit means 100, and thence to grounded battery 98. The cams 118 are secured to the shaft 102 by means of set screws 122 so that any number of these cams and corresponding contact means 114 may be provided in order that any desired number of code impulses common to each of the adjustable series of code impulses provided by the fingers 16 may be produced. It should be understood that the current impulses provided by the contact means 114 may be either entirely dispensed with or utilized to control apparatus remote from the circuit means

100 in timed sequence with the production of impulses by the contact means 26.

In operation, an operator manually depresses the knob 66 to move the shaft 20 in a downward direction against the action of the compression spring 60 so that the teeth 52 are moved out of engagement with the slots 54, and so that the cam arm 16 positioned below the disc 28 is moved out of engagement with the lowermost roller 72. The operator then manually rotates the knob 66 and the shaft 20 to a desired position as indicated by the co-operating pointer 68 and dial plate 70. At this time, pressure is removed from the knob 66 and the shaft 20 moves vertically upward as shown in Figs. 1 and 3 to move the desired code bar 16 into engagement with the roller 72 positioned thereabove. Simultaneously therewith, the teeth 52 engage with the slots 54 to hold the plurality of fingers 16 in the selected position. Thereupon, the operator energizes the motor 104 (Fig. 5) to rotate the shaft 102 and, consequently, the disc 28. As shown in Fig. 3, the disc 28 is rotated in a clockwise direction so that the roller 72 passes over a series of cam surfaces 18 formed in the uppermost edge of the operatively engaged finger 16 to produce intermittent reciprocation of the shaft 76. The intermittent reciprocations of the shaft 76 intermittently close the circuit between the grounded outermost and lowermost switch arm 86 and the lowermost inner switch arms 86 to complete an energizing circuit for the coding circuit 100 which comprises grounded lower switch arm 86, inner switch arm 86, slip ring 92, brush 96, conductor 94, coding circuit 100, and grounded battery 98. Simultaneously with the rotation of the disc 28 the plurality of cams 118 close a plurality of circuits from ground through switching means 114 and the conductors 120 for energizing the coding circuit 100.

Obviously, once the motor 104 has been energized, a new permutation of code impulses may be selectively produced under the control of the operator by merely depressing the knob 66 and turning the shaft 20 to move another of the plurality of fingers 16 into engagement with the rollers 72 of the actuating assemblies 24. Also, if the common impulse sequences produced by the plurality of cams 118 is not desired, these cams may be removed from the shaft 102.

It is to be understood that the above described embodiment is merely illustrative of the principles of this invention, and that numerous other modifications may be devised by those skilled in the art which will embody these principles and fall within the spirit and scope thereof.

What is claimed is:

1. An impulse producing device comprising fixedly mounted coded cam means, movable impulse producing means in operative engagement with said fixed cam means, fixedly mounted impulse producing means, movable cam means adapted to engage and operate said fixed impulse producing means, and means for simultaneously moving said movable means relative to said fixed means to operate both of said impulse producing means.

2. An impulse producing device comprising a frame, a first impulse producing means secured to the frame, a shaft rotatably mounted on the frame, second impulse producing means carried by the shaft, a plurality of cam means movably mounted on the frame, means for securing one of said plurality of cam means to the frame in operative engagement with the second impulse producing means for actuation thereby, cam means secured to the shaft for operating said first impulse producing means, and means for rotating the shaft to operate the first and second impulse producing means.

3. An impulse producing device comprising a frame, coded cam means mounted on the frame, a shaft rotatably mounted on the frame, a pair of contact means mounted on the shaft diametrically opposite each other, a pair of actuating means movably mounted on the shaft diametrically opposite each other, each of said actuating means adapted to operate one of said contact means and being engageable with the coded cam means, and means for

rotating the shaft to move the actuating means relative to the cam means whereby each contact means alternately produces a series of impulses under the control of the cam means.

5. In combination with an element having undulations thereon representative of intelligence, a supporting member, a plurality of contact means mounted on the supporting member, a plurality of actuating means movably mounted on the supporting means, each of said actuating means adapted to operate one of said contact means under the control of said element, and means for moving the supporting member to sequentially move each of the plurality of actuating means into engagement with and relative to the element for sequentially operating the plurality of contact means to produce a series of identical impulse sequences representative of the intelligence and under the control of the element.

5. An impulse generating device comprising a first impulse producing means for generating a fixed sequence of impulses, second impulse generating means for generating a variable sequence of impulses, a plurality of coded cams selectively movable into engagement with the second impulse producing means to control the operation thereof, means for movably supporting the second impulse producing means in engagement with the selected coded cam, means carried on said supporting means for operating the first impulse producing means, and means for moving the supporting means relative to the first impulse producing means and the selected coded cam to produce a series of impulses including a fixed sequence of impulses and a plurality of selectively variable impulses.

6. An impulse generator comprising impulse generating means, a supporting shaft, a plurality of coded members carried on the shaft and movable into engagement with the impulse generating means, means mounting said shaft for rotary and axial movement to permit selected coded cams to be moved into engagement with the impulse generating means, means for normally retaining said shaft in a selected rotated position with the selected coded member in engagement with the impulse producing means, axial displacement of said shaft moving the selected cam member out of engagement with said impulse generating means and rendering said retaining means ineffective so that said shaft can be rotated to select another of said cam members for engagement with said impulse generating means, and means for moving the impulse generating means relative to the selected coded member to generate impulses.

7. An impulse generating device comprising a frame, a shaft movably mounted on said frame, a plurality of arcuate elongated cam members, means for securing one end of each of said cam members to peripherally spaced positions on said shaft with the cam members extending radially outward from said shaft, impulse generating means mounted on said frame for rotation about a fixed axis, said axis being spaced from said cam members and located approximately midway between the free and supported ends thereof, and means for moving a selected one of said cam members into operative engagement with said impulse generating means.

8. An impulse generating means comprising a frame, a first shaft mounted for radial and axial movement relative to said frame, a plurality of cantilever cam members secured at one end to said shaft and extending radially outward therefrom, a second shaft rotatably mounted on said frame for rotation about an axis substantially perpendicular to the axis of said first shaft and spaced therefrom, impulse generating means carried by said second shaft, and means for moving said first shaft axially and radially to move a selected one of said cam members into operative engagement with said impulse generating means, said second shaft being located at a point spaced from and approximately midway between the free and supported ends of said selected cam member.

9. An impulse generating device comprising a frame, a shaft movably mounted on the frame, locating means

carried on said shaft and defining peripherally spaced positions, a plurality of elongated arcuate cam members, one end of each of said members being positioned at said spaced peripheral positions by said locating means, means for securing said ends in said locating means to provide a plurality of peripherally spaced cantilever cam members extending radially outward from the shaft, and impulse generating means in engagement with and movable relative to a selected one of said cantilever cam members.
